UNITED STATES PATENT OFFICE.

CHARLES L. RIDGWAY, OF BOSTON, MASSACHUSETTS, ASSIGNOR TO THE RIDGWAY FURNACE AND STOVE COMPANY, OF NASHUA, NEW HAMPSHIRE.

HEATING STOVE OR FURNACE.

SPECIFICATION forming part of Letters Patent No. 391,427, dated October 23, 1888.

Application filed March 1, 1886. Serial No. 193,583. (No model.)

To all whom it may concern:

Be it known that I, CHARLES L. RIDGWAY, of Boston, in the county of Suffolk and State of Massachusetts, a citizen of the United States, 5 have invented a new and useful Improvement in Heating Stoves and Furnaces, of which the following is a full, clear, and exact description, reference being had to the accompanying drawings, forming a part of this specification, 10 in explaining its nature.

The invention is an improvement upon that which is described in United States Patent No. 281,795, which was issued to me July 24, 1883. In said patent I have described a basket or 15 open fire-pot wall arranged within a chamber forming a downward extension to the combustion-chamber and adapted to be revolved.

In the present invention the fire-pot wall, while of similar form to that described in said 20 patent, in that it has vertical bars and vertical openings between the bars and is centrally arranged in a downward extension to the combustion-chamber, is not adapted to be revolved, and it is suspended from the inner casing or 25 wall of the furnace; and my present invention relates to the manner of suspending the fire-pot wall, and also to the construction of the same, all of which will hereinafter be fully explained.

30 Referring to the drawings, Figure 1 is a vertical central section of a portion of an air-heating furnace in which my improvements are embodied. Figs. 2 and 3 are details representing perspective views of fragments of 35 the fire-pot wall.

A is the ash-pit.

B is the fire-pot; C, the combustion-chamber; D, the fire-pot wall; d, the chamber about the fire-pot, which is in communication with 40 and constitutes a part of the combustion-chamber.

d' is the casing or shell which incloses the combustion-chamber, and forms, in connection with the fire-pot wall and its upper and lower 45 lateral exterior connections, the chamber d, already referred to, and d² is the exterior or hot-air casing of the furnace.

The fire-pot wall D comprises a series of sections, D', each of which is formed substantially 50 as represented in Fig. 2, and any suitable

number of sections are employed. Each section or segment has an upper horizontal curved bar or rim, d⁴, a lower horizontal curved bar or rim, d⁵, and intermediate vertical connecting-bars, d⁶. Each of these sections has also 55 an exterior stud, pin, or arm, d⁷, which projects horizontally outward from a point preferably near the center of the upper horizontal member, d⁴, of the section. These sections D' of the fire-pot wall are secured together by 60 means of an annular plate, E, a downwardly-extending flange, e, of which projects inside the upper extremity of the assembled sections of such wall, as represented in Fig. 1, and also in Figs. 2 and 3, taken together. The securing 65 plate E is provided also with exterior downwardly-extending projections or hooks, e², which upon slight rotation of the plate engage beneath the studs or arms d⁷ upon the part d⁴, thus securely connecting the several sections 70 or segments to the annular plate.

The lower bars or members, d⁵, of the sections D' extend into a recess, e³, which is provided in the upper and inner portion of a horizontal plate, F, and they are confined within 75 this recess by a sleeve or ring, G, which upon its upper extremity is provided with an exterior shoulder, g, which bears upon a corresponding inwardly-projecting ledge or shoulder of the member d⁵, or which extends into 80 a recess or groove, d⁷, formed in such member. This covering-ring or securing-sleeve G, preferably slightly tapered from top to bottom, as represented, extends downward to a point near the upper surface of the grate H. 85

For the suspension of the fire-pot wall the plate E is provided with exterior arms, E', which are received in suitable lugs or recessed brackets, E², which are secured to the wall of the combustion-chamber. The composite fire-pot wall thus constructed may, as is obvious, be readily lifted from its supporting brackets and the plate E detached, for the replacement of any of the sections which may have become imperfect through breakage or wear or for 90 nesting the sections for transportation.

The sectional or composite fire-pot wall herein described is similar in some respects to that shown in an application serially numbered 194,939, filed by me in the United States Pat- 95

ent Office on the 12th day of March, 1886; but it differs from that, in that the securing-ring is provided with projections, which are lacking in that construction, for the suspension of 5 the fire-pot from the wall of the combustion-chamber, and in that it does not rest upon and revolve with the revoluble plate.

Having thus fully described my invention, I claim and desire to secure by Letters Patent 10 of the United States—

1. A fire-pot wall which is composed of several vertical sections, each of which embraces a series of vertical bars which are separated by intermediate spaces, and which are connected by horizontal top and bottom bars or 15 rims, as set forth.

2. A fire-pot wall which is composed of a series of independent vertical sections, D', each having vertical bars and intermediate vertical 20 openings, in combination with top and bottom one-part devices for securing such sections rigidly together.

3. The combination of the sections D' of the fire-pot wall with the plate E, having the 25 downward interior projecting flange *e* and the outer inclosing or holding projections, *e*', all substantially as described.

4. The combination of the sections D' of the fire-pot wall, having the pins *d*', with the plate 30 E, having the flange *e* and the hooks *e*', substantially as described.

5. The combination of the sections D' of the fire-pot wall, having the pins *d*', with the plate E, the flange *e*, the hooks *e*', and arms or brackets for attaching the plate to the casing 35 of the furnace, substantially as described.

6. The combination of the sections D' of the fire-pot wall with the plate F, having the recess *e*', and the cylindrical section or sleeve G, all substantially as described. 40

7. In a heating stove or furnace, a fire-pot wall which has vertical bars which alternate with vertical spaces, and which is suspended by its upper edge within a chamber which constitutes a portion of the combustion-chamber, substantially as shown and described. 45

8. In a heating stove or furnace, a fire-pot wall which embraces a series of vertically-arranged vertically-barred sections, and a top engaging-plate which interlocks with each of the vertical sections, and which is provided with exterior arms, whereby the entire fire-pot wall is suspended at its upper extremity upon the wall of the combustion-chamber, as and for the purposes set forth. 50

CHARLES L. RIDGWAY.
